CENTRALIZED TRAFFIC CONTROLLING
SYSTEM FOR RAILROADSNeil D. Preston, Rochester, N. Y., assignor to
General Railway Signal Company, Rochester,
N. Y.

Application August 24, 1935, Serial No. 37,742

4 Claims. (Cl. 177—353)

This invention relates to centralized traffic control systems for railroads, and more particularly to a means for registering controls in a communication system of the multiple impulse or code type.

In the multiple impulse or code type communication system commonly employed in centralized traffic control systems for the purpose of governing the operation of switches and signals at a distant field station from a central control office, the controls for governing the operation of the switches and signals are transmitted by a series 10 of time spaced plus or minus impulses, or impulses otherwise distinguishable in character by 15 variable line circuit conditions or the like. These distinctive control impulses are employed to condition suitable relays at the field location governing the operation of power-operated track switches and the indications of their associated signals.

20 In one arrangement, such as disclosed for example in the prior application of Preston and Hitchcock, Ser. No. 455,304, filed May 24, 1930, corresponding to the British Patent No. 377,971, the character of the control impulse for each step 25 or time interval is registered by operating a two position polarized relay to one position or the other, the armature of said relay, conveniently termed a mag-stick relay, being magnetically held in the position to which it is set until 30 changed by some subsequent impulse. In such an arrangement, a control impulse to operate the mag-stick relay from its existing condition to another desired condition may not be effective, due to a broken wire or bad contact, or the 35 like, with the result that the desired control actually transmitted and received at the field location is not properly registered; and while the system for controlling the switches and signals 40 is so organized that no unsafe condition is produced by such failure, trains may be signalled to advance over a wrong route not desired by the operator.

In another arrangement for registering controls, neutral decoding relays, all de-energized at the beginning of a transmitting cycle, are selectively energized in accordance with the control code transmitted, and then the relays controlling the switches and signals are conditioned, provided the decoding relays have properly responded to the control code transmitted. This arrangement requires decoding relays, usually two for each step, in addition to the switch and signal control relays.

55 One object of this invention is to provide means

for registering the code character of the control impulses which is reliable in its operation but does not require the use of additional decoding means.

Generally speaking, and by way of explanation and without attempting to define the nature or scope of the present invention, it is proposed to employ neutral stick control relays directly responding in succession to the code character of the control impulses for the successive steps, these 10 relays individually or jointly controlling the operation of the switches and signals; and to control the stick circuits for each of these neutral stick control relays so as to be temporarily broken while an energizing or pick-up circuit for such 15 relay is opened or closed dependent upon the control impulse being transmitted, said stick circuits maintaining the control relay energized at other times to maintain the desired control effective.

20 Other characteristic features, attributes, and advantages of the organization of relays and circuits constituting the present invention will be in part apparent, and in part pointed out, as the description progresses.

25 The present invention relates to only a part of a complete system of code communication for centralized traffic control; and while it is contemplated that the invention will be used with the various features commonly employed or suitable for such a complete communication system, such as station selection, transmission of 30 indications, and the like, in order to simplify the disclosure and explanation of the present invention, such features of the complete system are 35 not illustrated and will not be described, except in a general way and in so far as appears to be necessary to understand the functions and mode of operation of the parts and circuits constituting this particular improvement.

40 In the accompanying drawings, Fig. 1 illustrates diagrammatically and with various conventional illustrations, one form of this invention; Fig. 2 illustrates one typical arrangement of circuits for operating the stepping relays; Fig. 3 is a diagram or chart showing, for explanatory purposes, the sequence of operation of certain relays particularly pertinent to an understanding of the present improvement; Fig. 4 shows how the organization of Fig. 1 may be used in a multiple 45 control station system with station selection; and Fig. 5 shows a modified organization.

50 For the purpose of simplifying the illustration and facilitating the explanation, the various relays and circuits have been shown diagrammati- 55

cally and conventionally, and the symbols (+) and (-) are employed to indicate connections to the opposite terminals of a battery or other suitable source of current for energizing the circuits, instead of showing all of the wiring connections that would be employed in practice.

Referring to the drawings, the central control office of this system is indicated by a dotted rectangle in the upper left-hand corner of Fig. 1. The code transmitting and receiving equipment in this control office is connected to the equipment at the various field stations by three line wires, comprising a stepping and control line wire SCL, an indication line wire IL, and a common return line wire CL. The stepping and control line wire SCL, together with the common return wire CL, constitute a stepping and control line circuit which is energized in the control office with a series of impulses of a selected polarity for operating stepping relays at the field location sequentially one at a time, and conditioning control relays for governing the operation of switches, signals, and the like. For the purpose of explaining and understanding the present improvement, it is considered unnecessary to illustrate the code transmitting equipment in the control office by which these series of impulses are applied to the stepping and control line circuit, first in accordance with the code call for a particular control station to be selected, and then in accordance with the position of switch and signal levers manually set by the operator for the purpose of controlling the operation of corresponding switch machines and signals.

It is contemplated that the controls for a power-operated switch or switches and associated signals will be transmitted as a group to each of the various control stations, one station at a time as the operator positions the switch and signal levers for these control stations and actuates corresponding starting buttons, in the manner disclosed for example in the application of Preston and Hitchcock, Ser. No. 455,304, May 24, 1930 or T. J. Judge and C. S. Bushnell, Ser. No. 640,062, filed October 28, 1932. These applications correspond respectively to British Patent No. 377,971 and U. S. Patent No. 2,082,544. It is also contemplated that the controls for a plurality of switches or for various routes may be transmitted, either simultaneously during the same operating cycle, or successively on different operating cycles, as best adapted to the particular track layout. For the purpose of explaining the nature of the present invention, the various ways of communicating controls to several control stations for various track layouts may be disregarded, and it is sufficient to consider this invention as applied to a single switch and its associated signals at one field location.

Disregarding the transmission of indications, station selection, arrangement and grouping of switch and signal controls, and other features characteristic of a complete system incorporating the present improvement, and considering this improvement as embodied in its simplest form, the field station equipment as shown in Fig. 1 comprises a three-position biased to neutral polar line relay F in the stepping and control line SCL; a neutral repeater line relay FP energized each time the line relay F is energized by closure of contact 8, irrespective of the polarity of such energization; a slow-release relay SA picked up at the beginning of each operating cycle and maintained picked up during such cycle even though the line relay F and its repeater FP are

only intermittently energized closing contact 9 for each impulse to energize relay SA; a group or bank of stepping relays 1V, 2V, etc., including a half-step relay VP; neutral stick control relays WN and WR governing the operation of the switch machine, and similar relays RD and LD for governing the clearing of the associated signals; and a special additional relay X for governing the stick circuits of the control relays WN, WR, etc.

Any suitable arrangement of stepping relays may be employed; and the particular stepping bank illustrated in Fig. 2, and corresponding to that disclosed in the prior application of T. J. Judge and C. S. Bushnell, Ser. No. 640,062, filed October 28, 1932, is merely typical. Since the circuit organization and mode of operation of this bank of stepping relays is explained in detail in said Judge and Bushnell application, and in its specific form constitutes no part of the present invention, it will be sufficient to point out generally certain characteristic features in the operation of this stepping bank.

During the conditioning period at the beginning of an operating cycle, relays F and FP are energized, and thereafter the relay SA, whereupon relay VP is picked up over a circuit that may be readily traced from (+), through front contact 10 of relay SA, front contact 11 of relay FP, back contacts 12, 13 and 14 of the stepping relays 3V, 2V and 1, relay VP to (-). Relay VP is maintained energized by a stick circuit through its contact 15 and back contacts of the stepping relays. When the line circuit is broken at the end of the conditioning period and relays F and FP are de-energized, the first stepping relay 1V is energized by a circuit readily traced in Fig. 2 from (+), through a front contact 16 of relay SA, back contact 17 of relay FP, front contact 18 of relay VP, and back contact 19 of relay 2V, said first stepping relay 1V, when energized, being maintained energized through its own front contact 20 and a stick bus 21 and front contact 16 of relay SA until the end of the operating cycle. While relay FP is de-energized, relay VP is held up by a stick circuit through back contact 11 of relay FP and front contact 22 of relay VP. When the line circuit is again energized, relay VP drops, relay 1V being now up. During the next de-energization of the line circuit, the next stepping relay 2V is energized through back contact 18 of relay VP, back contact 23 of 3V, and front contact 24 of 1V; and during the next following energization of the line circuit, relay VP again picks up to prepare the energizing circuit for the next stepping relay 3V. The same operation is repeated for as many steps as desired.

Thus, in accordance with the particular arrangement of stepping relays assumed for the specific embodiment of the invention illustrated in Fig. 1, after relay VP is initially energized during the first energization of the line circuit in the conditioning period, a stepping relay picks up during each succeeding de-energization or "off" period, and the relay VP shifts, i. e., changes from its energized or de-energized condition as the case may be, during each of the succeeding energization or "on" periods.

This operation of the stepping relays 1V, 2V, and 3V establishes sequentially local channel circuits for energizing the control relays WN, WR, RD and LD in accordance with the polarity of energization of the line relay F, during the next "on" period following the "off" period during

which the corresponding stepping relay was energized.

Referring to the control relay WN as typical, this relay is energized through its upper winding during the first stepping period when the line relay F is energized with a particular polarity and relay 1V is energized, this polarity in the case of the relay WN being assumed to be plus to set the polar contact of relay F to the right. This energizing circuit may be traced from (+), polar contact 25 of relay F to the right, back contacts 26 and 27 of stepping relays 3V and 2V, front contact 28 of relay 1V, through the upper winding of relay WN to (-).

15 Each control relay has a plurality of stick circuits for maintaining it energized, if energized, under different conditions. One of these stick circuits through the lower winding includes a back contact of the corresponding stepping relay, this stick circuit in the case of relay WN being readily traced from (+), through back contact 30 of relay 1V, front contact 31 of relay WN, and lower winding of relay WN to (-).

20 All of the control relays also have stick circuits through their upper windings connected to a stick bus 32 which is energized through back contacts 33 and 34 of relays FP and SA and front contact 35 of relay X in multiple.

25 Each control relay, except the one controlled on the last step, has a stick circuit through its lower winding including a front contact of the stepping relay next succeeding the stepping relay controlling the energization of such control relay. In the case of control relay WN, this supplemental stick circuit may be traced from (+), through front contact 36 of stepping relay 2V, front contact 31 of relay WN, and lower winding of relay WN to (-).

30 Considering now the sequence of operation, and referring to Fig. 3 for explanatory purposes, assume that the last switch control code was plus to energize relay WN and cause the switch machine to assume its normal position, and suppose that the operator sets the switch lever to the 35 reverse position and initiates the operation of the system. During the conditioning period, relays F, FP, SA, and VP are energized, and when relays F and FP are de-energized, following this conditioning period, the first stepping relay 1V is energized. This breaks the stick circuit for relays WN and WR through the back contact 30 of relay 1V; but relay FP is de-energized at this time and the stick bus 32 is energized through back contact 33 of relay FP to maintain relay WN energized by its stick circuit through its upper winding.

35 When the line circuit is again closed and energized with a minus polarity corresponding to the switch lever in the reverse position as assumed, the energizing circuit for relay WN is not closed, since the polar contact 25 of the line relay F moves to the left; but a similar pick-up circuit for energizing the relay WR is established. When the line relay repeater relay FP picks up and opens its back contact 33, the stick bus 32 is de-energized and the relay WN releases its armature.

40 It can be seen that when the line circuit is opened, after transmission of this control impulse, the line relay F assumes its de-energized condition and opens the energizing or pick-up circuit for relays WN or WR, as the case may be, before the line repeater relay FP closes its back contact to energize the stick bus 32; and in order to maintain energized the control relay that was 45 energized by the control impulse, relay X and its

energizing circuit controlled by relay VP and the stepping relays 1V, 2V, etc. are provided. Remembering that during the energization of the line circuit for conditioning relays WN or WR, relay VP is de-energized, it can be seen that an energizing circuit for relay X is established from (+), through back contacts 40, 41 of the stepping relays 3V and 2V, front contact 42 of relay 1V, back contact 43 of relay VP, and relay X to (-). This energization of relay X supplies current to the stick bus 32, and holds up relay WN or WR, as the case may be, during the time the energizing circuit for one or the other of these relays is broken at the polar contact 25 of the line relay F until line relay repeater FP closes its back contact 33. Relay X is not energized until relay VP has operated following energization of relay FP, and during this time relay WN or WR previously energized will have time to release its armature. In this connection, it may be stated that the purpose of using the relay X, rather than energizing the stick bus 32 directly through the contacts of relay VP and the stepping relays is to provide an additional relay operating time during which the control relay, such as WN may release its armature; and in this respect, the use of such a relay X is optional.

50 Following the energization period during which the control relay WN or WR is conditioned, in accordance with the polarity of such energization, as just described, the opening of the line circuit and de-energization of relays F and FP cause energization of the next stepping relay 2V, which closes through its front contact 36 the supplemental stick circuit to hold up WN or WR until the end of the cycle. Relay 2V also opens at its back contact 41 the energizing circuit for relay X and causes this relay to release its armature preparatory to the control of another control relay, such as RD, during the next succeeding 55 energization period.

55 This same operation is repeated for as many steps as desired; and in the same manner as described a pair of control relays, such as WN or WR, may be selectively conditioned on each step in accordance with the polarity of energization of the stepping and control line circuit. In the particular arrangement illustrated, the signal control relay RD is energized by a positive impulse on the second step, and the signal control relay LD by a positive impulse on the third step. This arrangement is merely illustrative of how a single relay may be energized or not on a particular step depending upon the polarity of the control impulse.

60 The circuits governed by control relays, such as WN and WR, are preferably organized in accordance with this invention, so that a relay of each pair for opposite or conflicting conditions must be energized while the other is de-energized in order to produce a controlling condition, there being no control exercised if both of these relays are either energized or de-energized. For example, in the particular arrangement illustrated, the switch machine SM is assumed to be constructed to respond to the polarity of energization of its control wires N and R, being provided with a polarized master relay as disclosed, for example, in the patent to W. K. Howe, No. 1,975,135, granted October 2, 1934.

65 With such an arrangement, if the control relay WN is energized and the other control relay WR is de-energized, the control circuit for the switch machine is energized with one polarity for the normal position through contacts 46 and 47 of 70 75

these relays, and if relay WR is energized while relay WN is de-energized, the switch machine control circuit is energized with the opposite polarity for the reverse position; but if both relays WN and WR are either energized or de-energized, the switch machine control circuit is not energized and the switch machine remains in its existing condition.

The signal clearing circuits are similarly controlled by contacts on the control relays RD and LD; and these signal clearing circuits are also controlled by the switch control relays WN and WR in opposite conditions, so that no signal clearing circuit is established, if both relays WN and WR, or both relays RD and LD, are either energized or de-energized. For example, taking the signal clearing circuit for signal IA as typical, this circuit may be traced from (+), through back contact 48 of relay LD, front contact 49 of relay RD, front contact 50 of relay WN, back contact 51 of relay WR, and thence through contacts (not shown) of a suitable point detector or switch position relay closed only if the switch points are over and locked in the corresponding normal position, with such other control of the clearing of the signal in accordance with traffic conditions, as may be desirable in accordance with the common practice in signalling systems of this character, such control of the signals in accordance with the positions of the switch point and the like being omitted.

In the particular arrangement shown, the pick-up and stick circuits for the signal control relays LD and RD include a front contact 52 of the detector track relay T, in multiple with a back contact 53 of the slow-release repeater TP of this track relay, in the manner characteristic of the disclosure in other prior applications, such as R. F. Wells, Ser. No. 634,370, filed September 22, 1932, so that the passage of a train de-energizes the relay LD or RD to cause the signals to assume the stop condition and remain at stop until cleared by some subsequent code, while permitting energization of these relays by a signal clearing code while the detector track circuit is occupied. Either signal control relay LD or RD, if energized to clear a signal, may be de-energized by the operator by sending a control code having an impulse on the respective steps controlling relays RD and LD of a polarity which does not close the energizing circuits for these relays.

From the foregoing it can be seen that, in accordance with this invention, the control relays governing the switch machines and signals at a field location are directly responsive to the character of the successive code impulses, and are selectively energized or de-energized successively as the impulses of the control code are transmitted, so that no additional decoding relays are required to register the control code step by step as transmitted prior to the conditioning of the switch and signal control relays. Even though the control relays are thus directly controlled, each control relay is positively rendered dependent upon the character of the corresponding control impulse, because it is a neutral relay and assumes its de-energized condition when its stick circuits are broken, unless an energizing or pick-up circuit is established. If such energizing or maintaining circuit for any control relay is not established on account of broken wires or bad contacts, such control relay assumes its de-energized or non-controlling condition, rather than remaining in the condition where last put. Consequently, circuit failures produce an inactive or non-control-

ling condition of the field equipment, rather than some controlling condition different from that transmitted.

Also, in accordance with this improvement, the pick-up or sustaining circuit for each control relay is established before its stick circuits are broken, so that a control relay does not release its armature even temporarily if the same control code is repeated. This feature is desirable, particularly in connection with the signal control relays RD and LD, because a temporary de-energization of one of these relays upon a repetition of the same signal clearing code might give a stop indication to confuse the engineer of an approaching train, particularly if color light signals are used.

In the organization of Fig. 1, just described, it is assumed that the desired controls are transmitted on each operating cycle for governing the control relays WN, WR, RD and LD illustrated, but in applying this invention to a multiple station system of the so-called duplex type, such as disclosed for example, in the application of Preston and Hitchcock, Ser. No. 455,304, filed May 24, 1930, there are conditions under which the field station apparatus, including the stepping relays, operates at a time when the proper controls for covering the control relays WN, WR, etc. are not applied to the stepping and control line circuit. Under such circumstances, it is necessary to provide means for holding the control relays WN, WR, etc. in their existing condition, except when controls are being transmitted to the particular control station in question; and such an arrangement is illustrated in Fig. 4.

Referring to Fig. 4, it is contemplated that a relay or relays, such as the relay SO, is energized when controls are being transmitted to the particular control station for governing the control relays WN, WR, etc. The specific type of station selecting or identification means is not material to the present invention; and the station selecting relay SO for out-bound controls shown in Fig. 4, which is assumed to be governed in the manner disclosed in the above mentioned Preston and Hitchcock application, Ser. No. 455,304, is merely typical.

Assuming such a suitable station selecting or identifying relay SO as shown in Fig. 4, the stick bus 32 for the control relay WN, WR, etc. is energized through a back contact 55 of this relay SO, and is connected to the bus wire 32¹ extending to the contacts 33, 34 and 35 of the relays FP, SA, and X. Also, the energizing circuits for the control relays WN, WR, etc. through the polar contact 25 of the line relay F includes the front contact 55 of the relay SO. During the station selecting steps, during which the continued energization of relay SO is determined, control relay WN or WR, as the case may be, is maintained energized by its stick circuit through the back contact of the stepping relay aV, corresponding to stepping relay IV of Fig. 1. Control relays RD and LD, and such others as may be employed, are similarly maintained energized by the stick circuits through the back contacts of the corresponding stepping relays bV, cV, and the like. If the control station in question is not called to receive new controls, relay SO is de-energized when the stepping relays aV, bV, etc. are operated, and the control relays WN and WR are maintained in their existing condition by their stick circuits energized from the stick bus 32, and no current is supplied to their energizing circuits since the front contact 55 of

relay SO is open. When the station is called to receive new controls, however, relay SO is energized at the time the stepping relay *aV* and the others for the control steps are energized; and under these conditions current is supplied to the polar contact 25 of the line relay F, and the energization of the stick bus 32 is controlled by relays FP, SA, and X, so that the control relays WN, WR, etc. are set or conditioned in accordance 10 with the control code in the same manner already described.

Fig. 5 illustrates a modification in which the line relay F¹ and the stepping relays *aV*, *bV*, etc. are equipped with special make-before-break 15 or continuity contacts in such a way as to simplify the circuit organization as illustrated in Fig. 1. The armature 60 of the line relay F¹, pivoted at its center, and biased by a spring 61 to the intermediate de-energized position shown, is 20 rocked and moves a contact driver 62 to the right or left, dependent upon the polarity of energization. Spring contact fingers 63, 64 are alternately shifted from the position shown to a dotted line position by the driver 62 as the line relay is 25 energized with current of opposite polarity, and open and close contacts suitably constructed, as indicated diagrammatically, to be make-before-break. Other contact fingers 65 supply current 30 to the line relay repeater FP whenever the line relay F¹ is energized with current of either polarity. The control relays WN, WR, and such others as may be used, have pick-up or energizing circuits through their lower windings, which are supplied with current through the contact 35 fingers 63 and 64, with relay SO energized and its front contact 66 closed, when the polar line relay F¹ is energized, in substantially the same way as shown in Fig. 1. The energizing circuit for WN, for example, may be traced from (+), front 40 contact 66 of relay SO, wire 67, contact finger 63 in the energized dotted position, wire 69, back contacts 70 and 71 of stepping relays *cV* and *bV*, front contact 72 of stepping relay *aV*, lower winding of relay WN to (-).

45 The two control relays for each step, such as WN and WR, have stick circuits including a back contact, as 73, of the corresponding stepping relay; and this contact of the stepping relay has a make-before-break front contact connected to 50 a stick bus 74. When the station is not being called and relay SO is de-energized, this stick bus 74 is permanently energized through the back contact 66 of the relay SO. When the station is being called, this stick bus is energized through 55 the front contact 66 of relay SO, wire 67, contact finger 63 of relay F¹ in the de-energized position, wire 68, and contact finger 64 in the de-energized position.

Considering the operation of this modification 60 shown in Fig. 5, assume that relay WN is energized, and that an impulse of opposite polarity is transmitted to the particular station in question on step *aV* for the purpose of de-energizing relay WN and energizing relay WR. During the 65 de-energization period of the line circuit next preceding the control impulse in question, the stepping relay *aV* is energized, breaking at its back contact 73 the stick circuit for WN, but simultaneously connecting this stick circuit to the 70 stick bus 74, which at this time is energized through contacts of the line relay F¹ and front contact 66 of relay SO. When the impulse of the selected polarity in question is applied to the line circuit and line relay F¹ is energized, its contact 75 finger 64 moves to the left in the case assumed,

establishing an energizing circuit for relay WR, and at the same time interrupting the supply of current to the stick bus 74. Relay WN then releases its armature, its stick circuit through its upper winding being broken at the contact 64 of line relay F¹, and the energizing circuit through its lower winding being opened at the contact 63 of said line relay. When line relay F¹ assumes its de-energized position, after the transmission of the control impulse in question, its contact finger 64 energizes the stick bus 74 and the stick circuit for relay WR now up, before the energizing circuit for relay WR is broken, due to the make-before-break construction of the contacts associated with said contact finger 64. During 10 this de-energization period, the next stepping relay *bV* is energized, and in this modification the stick circuit for the next preceding step relay *aV* includes a back contact 75 of the stepping relay *bV*, so that stepping relay *aV* drops and closes 20 the stick circuit for relay WR at its back contact 73, this stick circuit being closed prior to the interruption of the stick circuit to the stick bus 74, due to the make-before-break construction of these front and back contacts. This same plan 25 of operation takes place for as many steps as desired.

The modification of Fig. 5 employs make-before-break contacts on the polar line relay and on the stepping relays, so as to obtain the desired overlapping or continuity of the pick-up and stick circuits for the control relays, rather than dependent upon the sequence of relay operation as in the arrangement of Fig. 1. This modification of Fig. 5 has the various characteristic features and advantages already explained for the arrangement shown in Fig. 1, the control relays being set or conditioned, if at all, in accordance with the control impulse actually received, without relying upon the integrity of any 30 circuit, so that broken wires and bad contacts produce a non-controlling condition, rather than a controlling condition inconsistent with the control received. In this connection, it may be pointed out that in both of the arrangements 35 of Figs. 1 and 5, if the line relay during a given stepping interval should, for any reason, due to line surges or the like, shift its contacts quickly from one position to the other and simulate the condition of conflicting controls, the simultaneous energization of the pair of control relays 40 for that step, such as relays WN and WR by such improper double controls, if this should occur, is a non-controlling condition.

Various adaptations, and modifications may 55 be made in the particular arrangement of devices and circuits shown and described as exemplifying the invention, without departing from the fundamental functions and advantages of the invention; and means for receiving or registering controls in a centralized traffic control system, in accordance with this invention, may be employed in conjunction with various other features of a complete system.

What I claim is:—

1. In a remote control system of the multiple impulse or code type, an organization for registering controls transmitted to govern the operation of movable devices comprising, line wires for transmitting a series of code conditions each 70 controllable in character, step-by-step means operable to take one step for each code condition, a pair of neutral control relays associated with a particular step and each having energizing circuits, means for selectively energizing the en- 75

ergizing circuit for one or the other of said control relays on said particular step dependent upon the character of the code condition for that step, first and second stick circuits for each of said control relays, means for opening said first stick circuits only while said step-by-step means is operated for said particular step, and means for energizing said second stick circuits while said step-by-step means is thus operated for said particular step except for a time while one of said energizing circuits is closed.

2. In a remote control system of the character described, line wires energized distinctively to provide code impulses of different characters, a series of stepping relays, means for sequentially energizing said stepping relays one at a time for successive energizations of said line wires irrespective of the character of the impulses, a pair of neutral control relays associated with a particular step, means for energizing said control relays selectively in accordance with the character of the code impulse being transmitted, means for maintaining said control relays energized at all other times except while they are being thus conditioned in accordance with the character of the code impulse then being transmitted, and circuits governing the operation of a movable device closed only if said control relays are in opposite conditions of energization and de-energization.

3. In a remote control system; a stepping and control line circuit selectively energized with a series of positive and/or negative impulses; a polar line relay included in said line circuit; a neutral line repeating relay energized each time said polar line relay is energized irrespective of the character of the impulse; a series of stepping relays, means for energizing said stepping relays sequentially, one each time said line repeater relay is deenergized; a pair of control relays for each step; an energizing circuit for each control relay including a front contact of the corresponding stepping relay and a partic-

ular polar contact of said polar line relay so that one or the other of a pair of control relays is energized, while their stepping relay is picked up, dependent upon the polarity of the impulse then energizing said polar line relay; stick circuit means for maintaining said control relays energized, if picked up, at all times except a portion of that time while they are being conditioned in accordance with the polarity of the impulse transmitted while their respective stepping relays are picked up; electro-responsive means for each pair of control relays; and circuit means governing the operation of each electro-responsive device closed only if its said pair of control relays are in opposite conditions of energization and deenergization.

4. In a communication system of the remote control type; a line circuit having different series of time spaced characteristic impulses transmitted thereover; a line relay included in said line circuit; step-by-step means controlled by said line relay to take one step for each of said impulses; a pair of control relays associated with a particular step; first and second stick circuits for each of said control relays; means controlled by said step-by-step means for opening said first stick circuits during said particular step and at other times closing such stick circuits; means effective while an impulse is being transmitted during said particular step for momentarily opening said second stick circuits; station identifying means rendered effective only during particular ones of said different series of impulses; means controlled by the character of the impulse during said particular step, only if said station identifying means is rendered effective, for selectively energizing one or the other of said control relays during the time that both said first and second stick circuits are opened; and means controlled by said station identifying means, while rendered ineffective, for maintaining said second stick circuits closed.
